(57) **CLAIM**

The ornamental design for a counter light fixture, as shown and described.

DESCRIPTION

FIG. 1 is a front bottom right side perspective view of a first embodiment of the counter light fixture according to this invention;

FIG. 2 is a front view thereof;

FIG. 3 is a bottom plan view thereof;

FIG. 4 is a right end view thereof;

FIG. 5 is a left end view thereof;

FIG. 6 is a rear view thereof;

FIG. 7 is a top plan view thereof;

FIG. 8 is a view taken as in FIG. 1 of a second embodiment of my counter light fixture, the right and left end views thereof being identical to those of FIGS. 4 and 5 respectively;

FIG. 9 is a rear view thereof;

FIG. 10 is a top plan view thereof;

FIG. 11 is a view taken as in FIG. 1 of a third embodiment of my counter light fixture, the right and left end views thereof being identical to those of FIGS. 4 and 5 respectively;

FIG. 12 is a rear view thereof;

FIG. 13 is a top view thereof;

FIG. 14 is a view taken as in FIG. 1 of a fourth embodiment of my counter light fixture, the right and left end views thereof being identical to those of FIGS. 4 and 5 respectively;

FIG. 15 is a rear view thereof;

FIG. 16 is a top view thereof;

FIG. 17 is a view taken as in FIG. 1 of a fifth embodiment of my counter light fixture, the right and left end views thereof being identical to those of FIGS. 4 and 5 respectively;

FIG. 18 is a rear view thereof;

FIG. 19 is a top view thereof;

FIG. 20 is a view taken as in FIG. 1 of a sixth embodiment of my counter light fixture, the right and left end views thereof being identical to those of FIGS. 4 and 5 respectively;

FIG. 21 is a rear view thereof;

FIG. 22 is a top view thereof;

FIG. 23 is a view taken as in FIG. 1 of a seventh embodiment of my counter light fixture, the right and left end views thereof being identical to those of FIGS. 4 and 5 respectively;

FIG. 24 is a rear view thereof;

FIG. 25 is a top view thereof;

FIG. 26 is a view taken as in FIG. 1 of an eight embodiment of my counter light fixture, the right and left end views thereof being identical to those of FIGS. 4 and 5 respectively;

FIG. 27 is a rear view thereof;

FIG. 28 is a top view thereof;

FIG. 29 is a view taken as in FIG. 1 of a ninth embodiment of my counter light fixture, the right and left end views thereof being identical to those of FIGS. 4 and 5 respectively;

FIG. 30 is a rear view thereof; and,
FIG. 31 is a top view thereof.
